UNITED STATES PATENT OFFICE

122,876

DESIGN FOR A TITRATION APPARATUS ILLUMINATOR

Alexander I. Newman, Chicago, Ill., assignor to
Precision Scientific Company, Chicago, Ill., a
corporation of Illinois

Application July 17, 1940, Serial No. 93,732

Term of patent 7 years

To all whom it may concern:

Be it known that I, Alexander I. Newman, a citizen of the United States, residing at Chicago, in the county of Cook and State of Illinois, have invented a new, original, and ornamental Design for a Titration Apparatus Illuminator, of which the following is a specification, reference being had to the accompanying drawing, forming part thereof.

Fig. 1 is a perspective view of the titration apparatus illuminator showing my new design;

Fig. 2 is a top plan view thereof;

Fig. 3 is a rear elevational view, on a reduced scale.

The dominant features of my design reside in the portions represented in full lines. The burettes which are customarily positioned during use on the illuminator shown, are indicated in dotted lines.

I claim:

The ornamental design for a titration apparatus illuminator, substantially as shown and described.

ALEXANDER I. NEWMAN.
